UNITED STATES PATENT OFFICE.

JAMES WHITELY ALEXANDER, OF BRIDGEPORT, OHIO.

SMOKE-CONSUMER.

SPECIFICATION forming part of Letters Patent No. 621,197, dated March 14, 1899.

Application filed October 11, 1898. Serial No. 693,256. (No model.)

To all whom it may concern:

Be it known that I, JAMES WHITELY ALEXANDER, of Bridgeport, in the county of Belmont and State of Ohio, have invented a new and Improved Smoke-Consumer, of which the following is a full, clear, and exact description.

The object of the invention is to provide a new and improved smoke-consumer which is simple and durable in construction and arranged to draw the smoke, sparks, and cinders from the smoke-box of the boiler into the fire-box to be consumed therein with the burning fuel.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement as applied to a locomotive-boiler with part of the smoke-box broken out. Fig. 2 is an enlarged rear elevation of the same with part in section, and Fig. 3 is an enlarged rear end elevation of the same with parts in section.

The locomotive-boiler A, on which the improvement is applied, is provided with the usual smoke-box B, into which open the smoke-flues leading from the fire-box C. In the bottom of the smoke-box B is formed an opening B', leading to a casing D, from the sides of which extend the suction-pipes E, extending alongside the boiler to the casing F of the fuel-door, through which the fuel is passed to the fire-box C, the casing F extending a distance from said end of the boiler to accommodate the ends of the suction-pipes E, so that the smoke and cinders pass into the casing in front of the door F' and directly into the fire-box. Each suction-pipe is provided near its rear end with a valve E', and into each pipe near this end extends the nozzle of a pipe G, connected by a branch pipe G' with the steam-compartment of the boiler, so that steam under pressure can pass through the pipe G' into the pipes G and to the suction-pipes E, so as to create a suction therein to draw the smoke and cinders from the smoke-box B into the

casing F and fire-box C. The pipe G' is provided with a suitable valve G² for regulating the amount of steam passing into the suction-pipes E, the draft therein being regulated by the valves E'.

Directly over the opening B' in the bottom of the smoke-box B is arranged a bell-shaped deflector H, adjustably held on a rod I and adapted to be secured thereon by a set-screw H', the rod being held at its upper end in a cross-bar J, attached to the sides of the smoke-box, the lower end of the rod resting in a seat formed in the bottom of the casing D.

When the device is to be used, the valves E' and G² are partly or wholly opened, so that the steam passing into the suction-pipes creates a suction therein, as stated, to draw the smoke and gases from the smoke-box over the deflector H, down into the casing D, and from the latter through the pipes E into the door-casing F and to the fire-box C. The smoke, cinders, and sparks are thus returned in a very simple manner from the smoke-box to the fire-box to be consumed with the burning fuel.

It will be seen that the device is very simple and durable in construction, is not liable to get out of order, and the workings thereof are completely under the control of the fireman or engineer in the cab of the locomotive.

From the foregoing it is evident that the device may be readily applied to other boilers besides locomotive-boilers, as shown and described.

By having the deflector H arranged over the opening B' the cinders and sparks are more uniformly distributed. Moreover, as the cross-section is thus reduced at the opening B' the velocity of the draft is increased, carrying the cinders along forcibly and sometimes breaking them by throwing them against the walls of said opening, so that they will pass into the casing D and to the pipes E without danger of clogging the same.

Having thus fully described my invention, I claim as new and desire to secure by Letters Patent—

1. In a smoke-consumer, a smoke-box having an aperture in its bottom, a casing extending transversely under the smoke-box and communicating therewith through said opening, a deflector located in the smoke-box

above said opening and spaced therefrom entirely so as to form an annular channel around the deflector, pipes leading from the ends of said casing on each side of the boiler to the 5 fire-box, and means for creating a suction in said pipes to draw the cinders and smoke from the smoke-box to the fire-box.

2. In a smoke-consumer, a smoke-box having an aperture in its bottom, a vertically-10 adjustable deflector flaring toward its lower end and located above said opening so as to form an annular channel around the deflector, a pipe leading from the said opening to the fire-box, and means for creating in said 15 pipe, a suction toward the fire-box.

3. In a smoke-consumer, a smoke-box having an aperture in its bottom, a casing located under the smoke-box and communicating therewith through the said opening, an upright rod extending from the bottom of the 20 casing into the smoke-box through the opening thereof, a deflector located in the smoke-box and adjustable longitudinally upon said rod, a pipe leading from the casing to the fire-box, and means for creating in said pipe, a 25 suction toward the fire-box.

JAMES WHITELY ALEXANDER.
